UNITED STATES PATENT OFFICE.

NOAH EARLY, JR., OF WARRENSBURG, MISSOURI.

GATE.

SPECIFICATION forming part of Letters Patent No. 634,810, dated October 10, 1899.

Application filed July 17, 1899. Serial No. 724,119. (No model.)

To all whom it may concern:

Be it known that I, NOAH EARLY, Jr., a citizen of the United States, residing at Warrensburg, in the county of Johnson and State 5 of Missouri, have invented a new and useful Gate, of which the following is a specification.

This invention relates to gates, the object in view being to provide a gate especially 10 adapted for farm purposes and so constructed and arranged in connection with operating mechanism that the gate may be opened and closed by persons traveling on horseback or in vehicles without the necessity of such persons dismounting.

The primary object of the invention is to provide mechanism for opening and closing a gate which, while reliable in operation, is strong and durable and may be manufactured 20 at a minimum cost. The mechanism by means of which the gate is operated is of such a simple character that it may be readily set up adjacent to any gateway and connected with any form of hinged gate. The operating 25 mechanism also avoids the use of any small and delicate parts which are liable to become broken or get out of order, and said mechanism embodies sufficient strength and power to enable the gate to be operated in the 30 presence of high winds and under varying adverse conditions.

Other objects and advantages of the invention will appear in the course of the ensuing description.

35 The invention consists in gate-operating mechanism embodying several novel features and details of construction and arrangement of parts, as hereinafter fully described, illustrated in the drawings, and incorporated in 40 the claims.

In the accompanying drawings, Figure 1 is a perspective view of a gate and operating mechanism therefor constructed in accordance with this invention. Fig. 2 is a view in 45 elevation of the operating mechanism, looking toward the outside thereof or toward the roadway. Fig. 3 is a plan view of the same. Fig. 4 is an enlarged detail horizontal section taken in line with the crank-shaft and ratchet- 50 wheel shaft. Fig. 5 is a detail perspective view of the slide-bar, showing the manner in which it is mounted upon the supporting-

posts. Fig. 6 is a detail vertical section taken longitudinally between the supporting-bars and showing the ratchet-wheel, pawl, pawl-carrying arm, &c. Fig. 7 is a diagrammatic plan view illustrating the relative positions of the gate, slide-bar, and connections when the gate is open. Fig. 8 is a similar view showing the relation of the same parts when 60 the gate is closed.

Similar numerals of reference designate corresponding parts in all the figures of the drawings.

In carrying out the present invention I 65 employ in connection with the main gate-post 1, to which the gate is hinged, an auxiliary post 2, set at a distance therefrom and at the same side of the roadway as the post 1, the posts 1 and 2 being arranged in a plane parallel to the roadway and immediately at the 70 side thereof. The gate 3 may be of any usual or preferred construction and is hinged to the post 1. The preferred form of hinge consists of a vertical hinge-pin 4, which passes through 75 knuckles 5 at the upper and lower inner corners of the gate and also through stationary eyes or staples 6, projecting laterally from the posts. Several sets of eyes 6 may be employed in connection with such a gate and 80 hinge-pin, so that the gate may be adjusted in height or set higher or lower, according to the desire of the owner, it being frequently desirable upon farms to raise the gate above 85 the ground more or less for the purpose of enabling small stock to pass thereunder and for the additional purpose of enabling the gate, to be readily opened and closed in the winter-time when there is an accumulation 90 of snow, ice, &c.

I will proceed to describe the operating mechanism by means of which the gate may be thrown open or closed by persons while riding in a vehicle or upon horseback.

One of the essential elements of the operating mechanism consists of a sliding bar 7, which is mounted to reciprocate in suitable bearings on the posts 1 and 2, the line of said reciprocation of said bar being substantially parallel to the roadway. A convenient way 100 of mounting said reciprocating bar is to form recesses or mortises 8 in the posts 1 and 2, which mortises are of sufficient depth to receive the slide-bar 7, so that its outer surface

is flush, or substantially so, with the outer surfaces of the posts, the bar 7 being held in place by means of keepers 9, consisting of strips secured at their opposite ends to the 5 posts 1 and 2 above and below the mortises 8, as clearly illustrated in the drawings. Instead of extending the strips 9 entirely across the mortises 8 said strips may be made in two parts, as shown in connection with the 10 post 1, the inner adjacent ends of said part projecting sufficiently to overhang the mortise 8. The slide-bar 7 is provided with a laterally-projecting ear 10 upon its outer side or that side which faces away from the roadway, 15 said ear being designed for the pivotal connection thereto of one end of a link 11, the opposite end of which is pivotally connected to the side ear or lug 12 of an arm 13, projecting laterally from the gate, said arm being 20 preferably constructed from a metal strap bent to form inwardly-diverging arms or flanges 14, which are secured fast to one of the rails of the gate. This forms a rigid and well-braced arm on the gate, by means of which it 25 is designed to be connected to the operating mechanism. The link 11 has its outer end offset and bent downward to bring its extremity 15 into a lower plane than its main body portion, so as to pass over the upper 30 edge of the slide-bar 7 and connect pivotally to the ear 10 thereon.

From the foregoing description it will be understood that when the bar 7 is moved longitudinally in one direction the link 11 will 35 be drawn behind the gate-post 1 and will operate with a pulling action upon the lateral arm of the gate, thereby swinging the gate open until the free end of the gate strikes against the post 2. When the slide-bar 7 is 40 moved in the opposite direction, the outer end of the link 11 will be carried in the direction of the post 2, causing said link to operate with a pushing action upon the lateral arm of the gate, thereby closing the gate until its outer or free end strikes against the 45 post 16 at the opposite side of the roadway, in connection with which gate-post any suitable latch mechanism may be employed for holding the gate closed.

50 The shifting mechanism by means of which the slide-bar 7 is reciprocated consists of a shifting lever 17, which is fulcrumed at its upper end on the post 2 and has its lower free end connected by means of a pivotal link 18 55 with the slide-bar 7, as shown. At an intermediate point in its length the shifting lever 17 connects pivotally with one end of a connecting-bar 19, the opposite end of which is mounted upon the free end of a crank-arm 60 20 at one end of a crank-shaft 21, which is journalized in bearings in a pair of oppositely-arranged parallel bars 22, extending horizontally between the posts 1 and 2 and firmly secured to opposite sides thereof, so as to leave 65 an intervening space. The crank-shaft 21 is provided upon the end opposite the crank 20 with a spur-pinion 23, which is engaged and

operated by a spur-wheel 24, fast on a counter-shaft 25, also journalized in bearings in the bars 22 and having fast thereon between said 70 bars 22 a ratchet-wheel 26, which is operated by means of a pawl 27, pivotally mounted upon a pawl-carrying arm 28, journalized on the shaft 25 between the bars 22. The outer free end of the pawl-carrying arm 28 is connected by means of pivotal links 29 with the inner adjacent ends of a pair of operating-levers 30, fulcrumed intermediate their ends at 31 upon the posts 1 and 2 and having at their outer ends handles 32, which may be 80 grasped by the person riding in a vehicle or on horseback and pulled downward for correspondingly raising the inner adjacent levers and operating the gate-operating mechanism.

34 designates a detent which engages with 85 the wheel 24 for preventing retrograde movement of the ratchet-wheel shaft, and consequently of the crank-shaft.

From the foregoing description it will be seen that when either one of the operating-levers is moved or drawn downward at its outer end its inner end in moving upward will vibrate the pawl-carrying arm 28, causing the pawl 27 to partially rotate the ratchet-wheel 26 and shaft 25 and through the medium of the gears 24 and 23 partially turn the crank-shaft 21. The parts are so proportioned and related that the crank 20 will be turned through approximately a half-circle. In this movement of the crank-arm the shifting lever 17 will be vibrated through the medium of the connecting-bar 19, and by reason of its linked connection with the slide-bar the latter will be moved in one direction or the other. When one of the operating-levers 30 105 is again depressed, the crank-arm 20 will be carried through the remainder of its revolution and the shifting lever 17 will be vibrated in the direction opposite to that just described, causing the slide-bar to be moved also in the opposite direction. It will thus be seen that precisely the same means are employed for opening the gate as for closing the same. It will also be apparent that no small or delicate parts are employed in connection with the operating 110 mechanism, and said mechanism is thus not liable to get out of order and require frequent repairing. It matters not how high or how low the gate itself may be set the operating mechanism will be just as effective in one position as 115 in another. In order to insure the raising of the outer ends of the operating-levers 30 and the corresponding depression of the inner ends thereof, springs 33 may be employed, such springs being secured at one end of the posts 120 and 2 and bearing at their opposite or free ends beneath and against the outwardly-extending longer arms of the lever 30, the tension of said springs being exerted in an upward direction. The operating mechanism 125 is positive in action, serving to force the gate all the way shut or all the way open, and therefore does not depend upon gravity or auxiliary springs to complete the movement 130

of the gate in opening and closing which has been started by the operating mechanism.

The mechanism described and illustrated in the drawings is simple, effective, durable, 5 and reliable and may be manufactured at a small cost and set up at a price which will make it available for farming purposes and bring it readily within the means of the ordinary farmer.

From the foregoing it is thought that the construction, operation, and many advantages of the herein-described gate will be apparent to those skilled in the art without further description, and it will be understood 15 that changes in the size, shape, proportion, and minor details of construction may be resorted to without departing from the spirit or sacrificing any of the advantages of the invention.

Having thus described my invention, what I claim as new, and desire to secure by Letters Patent, is—

1. The combination with a gate, of a slide-bar operatively connected thereto for opening 25 and closing the gate, and ratchet-controlled mechanism for reciprocating said slide-bar.

2. The combination with a hinged gate, of a reciprocating slide-bar operatively connected thereto for opening and closing the 30 same, a shifting lever operatively connected to said slide-bar, and ratchet-controlled mechanism for operating said shifting lever.

3. The combination with a hinged gate, of a reciprocating slide-bar, working in a plane 35 parallel to the roadway, connections between said slide-bar and gate, a shifting lever operatively connected to said slide-bar, a crank-shaft for operating said shifting lever, and operating-levers having connection with said 40 crank-shaft.

4. The combination with a hinged gate, of a reciprocating slide-bar operatively connected thereto and operating in a plane parallel to the roadway, and ratchet-controlled 45 mechanism for reciprocating said slide-bar.

5. The combination with a hinged gate, of a reciprocating slide-bar, operatively connected thereto and working in a plane substantially parallel to the roadway, a crank- 50 shaft, connections between said crank-shaft

and the sliding bar, an operating-lever and connections between said lever and crank-shaft, substantially as described.

6. The combination with a hinged gate, of a slide-bar operatively connected thereto, a 55 crank-shaft, connections between said crank-shaft and slide-bar, a ratchet-wheel shaft geared to said crank-shaft, a ratchet-wheel thereon, a pawl-carrying arm journaled on said ratchet-wheel shaft, a pawl on said arm 60 engaging the ratchet-wheel, operating-levers extending in opposite directions, and connections between said operating-levers and pawl-carrying arm.

7. The combination with a hinged gate hav- 65 ing a laterally-projecting arm, of a slide-bar movable in a plane parallel to the roadway and having a linked connection with said lateral arm, and ratchet-controlled mechanism for reciprocating said slide-bar, substan- 70 tially as described.

8. The combination with a hinged gate having a lateral arm, of a slide-bar having a linked connection with said arm, distantly-located posts upon which said bar slides, parallel bars connecting said posts, a crank-shaft journaled in said bars, connections between said crank-shaft and slide-bar, operating-levers, and connections between said 80 levers and crank-shaft, whereby the crank-shaft may be partially and intermittently rotated, substantially as described.

9. The combination with a hinged gate, of a slide-bar moving in a plane parallel to the roadway, operative connections between said 85 slide-bar and gate, a crank-shaft, connections between said crank-shaft, and slide-bar, a counter-shaft parallel to said crank-shaft, intermeshing gears on said shafts, an operating-lever, connections between said lever 90 and counter-shaft for turning the latter, and a detent for preventing retrograde movement thereof, substantially as described.

In testimony that I claim the foregoing as my own I have hereto affixed my signature in 95 the presence of two witnesses.

NOAH EARLY, JR.
